UNITED STATES PATENT OFFICE

168,028

DESK

Arthur O. Garrett, San Marino, Calif.

Application February 20, 1950, Serial No. 8,023

Term of patent 14 years

(Cl. D33—7)

To all whom it may concern:

Be it known that I, Arthur O. Garrett, a citizen of the United States of America, resident of San Marino, in the county of Los Angles, State of California, have invented a new, original, and ornamental Design for a Desk, of which the following is a specification, reference being had to the accompanying drawing, forming a part thereof.

In the drawing:

Fig. 1 is a rear perspective view of a desk, showing my new design;

Fig. 2 is an end elevational view of the desk taken from the left hand side of Fig. 1;

Fig. 3 is an end elevational view of the desk taken from the right hand side of Fig. 1;

Fig. 4 is a front elevational view of the desk;

Fig. 5 is a top plan view of the desk taken on the line 5—5 of Fig. 1; and

Fig. 6 is a front perspective view of the desk.

I claim:

The ornamental design for a desk, as shown.

ARTHUR O. GARRETT.
